MANUFACTURE OF HYDROGEN FLUORIDE

Edwin B. Lopker, Oaklyn, and John E. Peirce,
Arlington, N. J., assignors to Allied Chemical &
Dye Corporation, a corporation of New York

Application March 14, 1946, Serial No. 654,456

2 Claims. (Cl. 23—153)

1

This invention relates to the manufacture of hydrogen fluoride.

In general, prior processes for making anhydrous liquid HF are such as to require use of substantial quantities of extraneous refrigerating agent or a fractional distillation step. This invention aims to provide a process which does not embody either of these features and which, in a practical sense, is self-refrigerating.

The invention, its objects and advantages appear from the following description taken in connection with the accompanying drawing diagrammatically showing one form of apparatus in which the process of this invention may be carried out.

Referring to the drawing, 10 indicates a conventional furnace in which fluorspar and sulfuric acid are reacted in the usual way to form a crude HF gas containing, for example, by weight 70% or more HF, 2% SiF_4 , some sulfuric acid mist, and air. The furnace gas, usually at temperatures of 105 to 115° C., is introduced into the bottom of a packed tower 11, and contacted therein countercurrent with strong sulfuric acid which is recirculated by means of the apparatus including a sulfuric acid discharge pipe 12, sump tank 14, pump 15, cooler 16 and return pipe 18 thru which acid may be sprayed into the top of the tower thru a suitable distributor. The purpose of tower 11 is to dry the gas and remove solid impurities. The liquor circulating system is operated so that the sulfuric acid fed into the top of the tower is at temperature of not less than 80-90° C., such temperature being maintained so as to minimize absorption of HF out of the gas stream. In order to effect efficient drying, the H_2SO_4 content of the liquor in tower 11 is kept high, and usually the liquor fed in thru pipe 18 contains about 88.2% H_2SO_4 , 1.8% water and 10% absorbed HF. Liquid discharged into the sump tank thru pipe 12 ordinarily contains about 87.3% H_2SO_4 , 2.7% H_2O , and 10% absorbed HF. To keep the H_2SO_4 strength of the circulating liquor at the desired relatively high concentration, SO_3 , preferably in the form of oleum, is fed into the circulating system thru pipe 22 in quantity such as to form about 97% H_2SO_4 with all of the water vapor entering from furnace 10.

Drying tower exit gas flows thru conduit 23 into a separator 24 which may be of any suitable type to effect substantially complete separation from the gas stream of any entrained sulfuric acid mist. In the practice of this invention, the crude HF generating process and apparatus units so far described are carried out and designed so as to form in separator exit pipe 26 a gas which 55

2

contains by weight not less than 70% HF, not more than 0.5% H_2O and substantially no sulfuric acid mist. Ordinarily, the water content of this gas is preferably not more than 0.1% by weight.

The incoming gas stream, which now may be at temperature of 70-75° C., passes thru a control valve 30 and pipe section 31 to the suction side of a compressor 33. The latter is preferably of 10 the turbine or screw type in which construction is such that no contact between the HF gas and lubricant is permitted. In pipe section 31, the incoming HF gas is mixed with recycled anhydrous HF vapor which is formed in a subsequent 15 step in the process.

In accordance with this invention, the HF content of the incoming gas is substantially completely liquefied without the use of extraneous refrigerating agent. To this end, the combined 20 gas stream in pipe 31 is first compressed to a substantial superatmospheric pressure. While extent of compression may vary over a relatively wide range, depending upon the particular conditions, ordinarily the gas is compressed to a 25 pressure of not less than 20 lbs. gauge and pressure may be as high as 70 lbs. gauge. In the compression step, a substantial amount of heat is generated. The hot gas stream is subjected to a preliminary cooling operation in which 30 enough heat is removed from the gas to effect liquefaction of a substantial quantity of HF. Such cooling operation may be stepwise and involve passage of the compressed gas thru several coolers connected in series, or this preliminary 35 cooling may be effected in a single step as exemplified herein. Thus, the gas stream is passed thru pipe 34 into a cooling zone 35 surrounded throughout its length by a chamber 36 thru which water may be passed, in indirect heat transfer 40 relation with the gas stream in zone 35, by means of valve controlled inlet and outlet pipes 38 and 39. It will be understood that pipes 38 and 39 are connected with a suitable water cooling and circulating system, not shown, designed 45 so as to effect flow thru cooling chamber 36 of whatever quantities of water may be needed to effect the desired cooling in zone 35.

In practice, flow of water or other suitable medium thru chamber 36 is regulated so that the 50 temperature of the gas stream exiting zone 35 at outlet 41 may be within the range of 25-45° C. and usually is around 30-40° C. At atmospheric pressure, anhydrous hydrogen fluoride gas condensed at about 19-20° C. and below. Since the 55 condensation temperature is higher at the super-

atmospheric pressures of operation, the temperature differential between the condensation temperature of the gas and the temperature existing at the outlet of zone 35 is relatively narrow, and a substantial quantity of the HF condenses. Assuming a given set of operating conditions—i. e. constant input of raw HF gas for a given composition, constant speed of operation of compressor 33, given cooling conditions in preliminary condensing zone 35, and recycling of a given quantity of anhydrous HF vapor as to be subsequently more fully described—the quantity of HF which is condensed in the preliminary cooling zone 35 corresponds approximately with the "make" of the process. The gas stream leaving preliminary cooling zone 35 thru outlet 41, containing liquefied and unliquefied HF and while still at the prevailing pressure, is introduced into a final cooling zone 44 provided substantially throughout its length with a jacket 45 which forms a vaporizing chamber 46 surrounding the gas cooling zone 44 in indirect heat transfer relation.

The cooling effected in zone 44 is such as to cause liquefaction of substantially all of the uncondensed HF. Cooling may be such as to reduce temperature of the gas stream and contained HF to a temperature substantially below the condensation point of HF at the prevailing pressure, e. g. to temperature of 5° C.-zero° C. or below. In any case, temperature existing in tank 50 should be low enough under particular conditions of operation, as to minimize the amount of HF vapor in the gas space of the collecting tank.

In accordance with the invention, the anhydrous liquid HF recovered in tank 50 is forced, by the pressure existing in the system, thru pressure reducing valve 51 and a pipe 52 into the vaporizing zone 46. In this zone, enough of the liquid HF is vaporized in indirect heat transfer relation with the residual gas mixture in final cooling zone 44 to effect the condensation therein of residual uncondensed HF. The amount of liquid HF vaporized in zone 46 depends upon the degree of heat removal from the system in the preliminary cooling zone 35, the temperature of the gas stream entering the final cooling zone 44, and the amount of uncondensed HF present. The vaporizing zone 46 communicates thru pipe 55 with pipe 31 and the suction side of compressor 33.

Assuming a given speed of operation of compressor 33, the amount of vaporization of liquid HF effected in zone 46, and corresponding heat transfer from final cooling zone 44, may be regulated by adjustment of valve 30 in incoming HF gas line 26. Thus, if the temperature of the gas stream entering final cooling zone 44 and the amount of unliquefied HF are relatively high, valve 30 may be closed sufficiently to proportionately increase the amount of anhydrous HF vapor drawn into pipe 55 and correspondingly increase the amount of liquid HF vaporized in zone 46. Conversely, if the gas stream introduced into final cooling zone 44 is at relatively low temperature and contains a smaller amount of unliquefied HF, a smaller degree of heat transfer in cooling zone 44 is necessary, and the amount of vaporization effected in vaporizing zone 46 may be cut down as required by opening valve 30 and correspondingly reducing the amount of anhydrous HF vapor drawn thru pipe 55 back to the inlet side of compressor 33. Thus, assuming a given set of cooling conditions in preliminary

70
75

zone 35, by simple adjustment of valve 30, depending upon the particular operating conditions at hand, the compression stage of the instant process may be so regulated as to effect vaporization of enough liquid HF in the vaporizing zone 46 to refrigerate the residual gas mixture sufficiently to cause condensation of substantially all of the uncondensed HF present in the final cooling zone.

10 It will be noted that the gas in compressor exit pipe 34 contains heat of compression, the sensible heat of the incoming HF gas, heat of vaporization of the HF in the incoming gas, plus whatever heat of the atmosphere may be transmitted inwardly to the system, i. e. atmospheric heat drawn in thru the walls of the apparatus comprising the final cooling stage, the collecting tank 50 and associated pipe connections. In accordance with this invention, all the heat that 15 is required to be abstracted from the system is removed by the cooling water circulating thru chamber 36. By use of ordinary water cooling and circulating apparatus it has been found to be readily possible to remove all required heat 20 from the process, and maintain temperature in the exit gas of the preliminary cooling operation at about 25-45° C. without difficulty

25 The invention affords the marked advantages that some of the sought-for product itself provides the final refrigeration, and whatever heat must be removed from the system may be taken out in a commercially feasible way by simple heat transfer to water which need not be maintained at temperatures lower than can be conveniently obtained, even in summer, by readily operated and controlled water cooling equipment. For any given crude HF gas and overall design of equipment, the process has only one major point of operating control, namely, the 30 quantity of water which is circulated thru water cooling chamber 36. For any specific set of operating conditions, the amount of anhydrous HF which is vaporized and recirculated thru the compressor is relatively constant. Under most 35 conditions met in practice, the volume ratio of incoming HF gas to recirculated anhydrous HF vapor may vary from say 1:1 to 1:4. Since as previously explained, the quantity of HF which is condensed in the preliminary cooling zone 35 corresponds approximately with the "make" of the process, when recycling HF gas under conditions such that the volume ratio of incoming HF gas to recirculated anhydrous HF vapor is about 1:4, about 20% by weight of the total HF present 40 in zone 35 condenses. Similarly, when working with ratios of 1:2 and 1:1, respectively about 33% and 50% by weight of the total HF present in zone 35 condenses. In the more unusual but possible circumstance in which the volume ratio of incoming HF gas to recirculated anhydrous HF vapor is about 1:0.5, approximately 66% by weight of the total HF present in zone 35 is liquefied therein.

45 The HF content of the incoming gas constitutes the "make" of the process and is drawn out as liquid from the lower portion of the vaporizing zone 46 thru pipe 68, which may be provided with a valve, into product tank 61. The latter is maintained under atmospheric pressure, and if desired may be provided with insulation or other means so as to maintain the temperature of the product at a temperature appreciably below the boiling point thereof. Thus the procedure of the invention provides for the manufacture of anhydrous HF without the necessity

of using extraneous refrigerating agent or requiring a final fractionation step such as is used widely in current operations.

The inert gas mixture collecting in the gas space in receiving tank 50 passes thru a reducing valve 62, and pressure is reduced to substantially atmospheric. The gas thus passes into the bottom of a tail gas clean-up tower 64 into the top of which cold strong e. g. 98-99% sulfuric acid is fed thru inlet 65. Preferably the tower is equipped with cooling coil 67 by which temperatures in the tower may be maintained low enough, e. g. 30° C., to effect absorption by the sulfuric acid of any relatively small quantities of HF which may be entrained in the tail gas discharged from receiver 50. At temperatures of around 25-40° C. sulfuric acid absorbs HF and separates the same from any SiF₄ and other inert gases which may be in the gas stream. The effluent liquor of tower 64 may be run thru line 69 into the top of drying tower 11 which, as previously stated, is operated at temperatures high enough to prevent absorption in the sulfuric acid of substantial amounts of HF. Thus, any HF which may be picked up in tail tower 64 is stripped out in tower 11 and recirculated as a constituent of the incoming HF gas. All of the SO₃ which is brought into the process either as 98% sulfuric acid fed to tail tower 64 or as oleum introduced thru pipe 22 is eventually withdrawn from the system thru an outlet pipe 71 and may be utilized for decomposition of fluorspar in furnace 10.

We claim:

1. The process for making substantially anhydrous hydrogen fluoride which comprises contacting crude HF furnace gas with strong sulfuric acid maintained at temperature above 90° C. and under conditions to dry said crude gas, and separating from the dried gas any entrained sulfuric acid mist to thereby form a gas mixture containing not less than 70% by weight of HF and not more than 0.5% by weight of H₂O, introducing said gas mixture into a compression stage, compressing such gas mixture therein to substantial superatmospheric pressure whereby heat is developed in said gas mixture, removing heat from the compressed gas mixture in a cooling operation by indirect heat transfer to water under conditions to effect condensation of at least a substantial portion of the HF content of said compressed mixture, introducing the residual gas mixture containing residual uncondensed HF into a final cooling stage, collecting liquid HF, vaporizing a portion of said liquid HF in indirect heat transfer relation with said residual gas mixture in said final stage, and recycling the thus vaporized HF with the incoming gas mixture at a point just ahead of said compression stage, regulating the volume ratio of incoming HF gas to recycled HF gas entering the compression stage to control the amount of HF thus vaporized and recycled thereby to refrigerate such residual gas mixture sufficiently to effect condensation in said final

stage of substantially all of the residual uncondensed HF, regulating said water cooling operation so as to effect removal thereby of substantially all heat required to be extracted from the system, passing the tail gas of said final cooling stage into contact with strong cold sulfuric acid to absorb any HF contained in said tail gas, and then passing said sulfuric acid into said crude gas drying operation.

5 10 15 20 25 30 35 40 45

2. The process for making substantially anhydrous hydrogen fluoride which comprises introducing a purified HF furnace gas mixture containing not less than 70% by weight of HF and not more than 0.5% by weight of H₂O, into a compression stage, compressing such gas mixture therein to a pressure of not less than 20 lbs. gauge whereby heat is developed in said gas mixture, removing heat from the compressed gas mixture in a cooling operation by indirect heat transfer to water under conditions to effect condensation of at least a substantial portion of the HF content of said compressed mixture and to bring the temperature of the exit gas within the range of 25°-45° C., introducing the residual gas mixture containing uncondensed HF into a final cooling stage, collecting liquid HF, vaporizing a portion of said liquid HF in indirect heat transfer relation with said residual gas mixture in said final stage and recycling the thus vaporized HF with the incoming gas mixture at a point just ahead of said compression stage, regulating the volume ratio of incoming HF gas to HF vaporized and recycled to a value in the range approximately 1:0.5 to approximately 1:4 thereby to control the amount of HF thus vaporized and recycled, said amount being sufficient to refrigerate such residual gas mixture sufficiently to effect condensation in said final stage of substantially all of the residual uncondensed HF and to bring the temperature of said HF condensate below about 5° C., regulating said water cooling operation so as to effect removal thereby of substantially all heat required to be extracted from the system, and passing the tail gas of said final cooling stage into contact with strong cold sulfuric acid to absorb any HF contained in said tail gas.
